UNITED STATES PATENT OFFICE

WALTER REMPEN, OF HANNOVER, GERMANY, ASSIGNOR TO AARON M. SLOSS, OF NEW YORK, N. Y.

STOVE FOR BURNING DISINTEGRATED LIGNITE COKE

Application filed January 28, 1929, Serial No. 335,659, and in Germany September 1, 1928.

This invention relates to a stove, in which means are provided for conveying the disintegrated lignite coke radially outwards from the delivery aperture of the fuel receptacle 5 to a plate supporting the burning coke. The bottom of the fuel receptacle is formed as a hopper, and a conveying member, formed preferably by a disk with horizontally extending blades, is arranged below the delivery opening of said hopper-shaped bottom. Also the fuel plate is, as a rule, hopper-shaped, and the conveying member, i. e. the disk with its blades, is located between said two hoppers. The fuel supporting plate or hopper receives the fuel by the intermediary of the said conveying member, and the means for turning this member extends through the fuel receptacle to the space above the stove, all as more fully described hereinafter. 10 The invention is illustrated diagrammatically and by way of example in the accompanying drawing in which,

Figure 1 is a vertical section through a stove designed according to this invention, Figure 2 shows a few details in plan, and Figure 3 shows only the lower part of the stove, drawn to an enlarged scale.

In the drawing, *a* denotes a disk secured to the lower end of a vertical shaft *b* provided at its upper end with a double handle *c* by which the disk *a* can be turned. This disk is provided with two practically tangentially arranged blades *d*. The arrows (Fig. 2) indicate the direction in which the disk with its blades is to be turned by the handle *c*.

The disintegrated coke is received in a vertical receptacle *e*, through the axis of which the shaft *b* extends. The bottom of the receptacle *e* is formed as, or by, a hopper *f*. Below this hopper is another hopper *g*, that is to say, a hopper-shaped fire plate upon which the glowing coke is supported. The fresh coke moves from the interior of the receptacle *e* into the annular space between the hoppers *f* and *g* where it is burned to ashes. These latter are removed by a scraper *h* affixed to the lowermost end of the shaft *b*. There may be more than one scraper so that turning the shaft *b* by only a few degrees will be sufficient to remove the ashes from

the burning coke, and to throw it down into a third hopper *p* through which it falls into the ash-pit *i*. The waste gases escape through the branch *k*. *m* denotes a conical cover which is however, open in its middle portion. 55

The double handle *c* is removable from the shaft *b*. The uppermost end of this latter is square, and the centre portion of the handle has an aperture of corresponding shape. When the handle has been drawn off the shaft, also the cover *m* can be removed, and now the interior of the receptacle *e* is completely open so that the disintegrated coke can be conveniently introduced into it. Thereafter the cover *m* is again placed on the receptacle and the handle *c* is put upon the shaft *b*. The fuel which is held within the receptacle *e* rests partly in the hopper shaped bottom *f* and some of it passes through the central opening of this hopper and rests upon the disc *a* which serves to prevent too rapid movement of the fuel through the bottom of the hopper. Some of the fuel falls into the spaces on each side of the blades *d*. When the disc *a* is revolved by the operation of 60 the handle *c* in the direction indicated by the arrows in Figure 2, the blades *d*, by reason of their tangential position on the disc *a*, tend to force the fuel outwardly from the periphery of the disc so that the fuel in the lower portion of the hopper *g* is pressed outwardly in the conical space formed between the hopper *f* and the member *g*. This causes the fuel to be fed upwardly to the point adjacent the outer edge of the member *g* where 65 the combustion takes place. From time to time as the shaft *b* is operated the scraper *h* removes the ashes formed by the burning of the fuel and the blades *d* force fresh fuel outwardly to take the place of that which 70 is consumed adjacent the edge of the member *g*. The disk *a* may have more than only two blades *d* whereby the conveyance of the coke will be rendered more uniform. 75

The combustion air enters the stove from below between the ash-pit *i* through bottom openings *l'* and the stove wall *l*. The upwardly directed arrows in Figs. 1 and 3 indicate its path. The air is heated while passing through the space between the hoppers *g* 80

and p , and streaming past the zone containing the glowing coke. The combustion gases escape through the branch k , as already stated. If the chimney draft is particularly strong, the receptacle c and the wall l may be arranged eccentrically with respect to one another, in such a manner, that the narrower portion of the cylindrical space between said parts e and l is on that side where there is the branch k . Another means for the same purpose is shown in Fig. 1, in which a baffle member o is arranged in said cylindrical space just below the said branch. Either means will render the heating of the wall l more uniform if the draft in the chimney is very strong.

The blades d may be a little inclined in vertical direction, in such a manner, that they exert upon the coke a corresponding upward pressure under which it is more easily conveyed upwardly into the space between the hoppers f and g .

As the combustion air, on its way from the stove bottom to the above-mentioned cylindrical space, streams past the top of the hot ashes, it is preheated at the same.

In the constructional form of the stove, as shown by way of example, the wall l is surrounded with a shell n forming with said wall a tubular space through which air can circulate.

At the same time the shell protects the persons present in the neighbourhood of the stove from being subjected too strongly to the heat radiated from the wall e .

I claim:

1. A stove for burning disintegrated lignite coke, comprising, in combination, a receptacle adapted to receive the fuel, a plate arranged below said receptacle, a disk arranged between the said receptacle and said plate, and blades extending substantially tangentially from said disk, said disk with its blades being adapted to move the fuel from the fuel receptacle outwardly in the space between this latter and the said plate.

2. A stove for burning disintegrated lignite coke, comprising, in combination, a receptacle adapted to receive the fuel, a plate arranged below said receptacle, a disk arranged between the said receptacle and said plate, and inclined blades extending from said disk, said disk with its blades being adapted to move the fuel outwardly in the space between said receptacle and the said plate.

3. A stove for burning disintegrated lignite coke, comprising, in combination, a receptacle adapted to receive the fuel, a plate arranged below said receptacle, a member arranged between the said receptacle and said plate and adapted to move the fuel outwardly in the space between the receptacle and plate, and means for turning said member, said latter means extending upwardly from

said conveying member through the fuel receptacle and accessible for operation at the top of the stove.

4. A stove for burning disintegrated lignite coke, comprising, in combination, a receptacle adapted to receive the fuel, a plate arranged below said receptacle, a disk arranged between the said receptacle and said plate, blades extending horizontally forth from said disk at angles of about 45° , a shaft connected firmly with said disk and extending upwardly through the coke receptacle, to the space above the stove, and a handle attached to the upper end of said shaft.

5. A stove for burning disintegrated lignite coke, comprising, in combination, a receptacle having a hopper-shaped bottom and being adapted to receive the fuel, a hopper-shaped member arranged below said bottom and spaced therefrom and a member arranged between said two hoppers and adapted to move the fuel outwardly in the space between the said hoppers; a shaft connected with said hopper-shaped member and extending upwardly through said receptacle to the space above the stove, and a handle attached to the upper end of said shaft.

6. A stove for burning disintegrated lignite coke, comprising, in combination, a receptacle adapted to receive the fuel, a plate arranged below said receptacle, a conveying member arranged between the said receptacle and said plate and adapted to move the fuel outwardly in the space between said receptacle and said plate; an ash-pit arranged below said plate, a wall surrounding and enclosing all above-mentioned members, said wall together with the fuel receptacle forming a tubular space, and another plate extending from said wall over the top of said ash-pit, substantially and for the purpose set forth.

7. A stove for burning disintegrated lignite coke, comprising, in combination, a receptacle having a hopper-shaped bottom and being adapted to receive the fuel, a hopper-shaped member arranged below said bottom spaced therefrom, and a member arranged between said two hoppers and adapted to move the fuel outwardly in the space between the said hoppers; a wall surrounding and enclosing all above-mentioned members, said wall forming with the fuel receptacle a tubular space, and another hopper-shaped member extending from said top over the wall of said ash-pit, substantially and for the purpose set forth.

8. A stove for burning disintegrated lignite coke, comprising, in combination, a receptacle adapted to receive the fuel, a plate arranged below said receptacle, a member arranged between the said receptacle and said plate and adapted to move the fuel outwardly in the space between said receptacle and

5 said plate; a wall surrounding and enclosing all above-mentioned members, said wall together with the fuel receptacle forming a tubular space, and a shell surrounding and enclosing said wall and forming together with the same a tubular space, substantially as, and for the purpose, set forth.

10 9. A stove for burning disintegrated lignite coke comprising in combination a fuel receptacle having a frustro conical shaped bottom and adapted to receive the fuel therein, a frustro conical member arranged below the bottom of said receptacle substantially parallel with and spaced from the frustro 15 conical bottom wall of said receptacle to form a frustro conical fuel space extending upwardly and outwardly from the lower end of said receptacle, and a member arranged between said bottom wall of the receptacle and said frustro conical member, and adapted to move the fuel upwardly and outwardly in said space between said frustro conical members.

15 In testimony whereof I affix my signature.
20 WALTER REMPEN.
